RECEPTACLE CLOSURE

Charles G. Nathe, Jr., St. Cloud, Minn.

Application May 7, 1932, Serial No. 609,866

17 Claims.

(Cl. 215—5)

This invention relates to improvements in milk bottle caps and has, as its principal object, to provide a cap, a portion of which is capable of being moved and manipulated to form a spout.

5 I am aware that heretofore milk bottle caps have been provided with a pouring opening covered with a pull-tab, so that when the tab is properly moved, milk can be poured from the opening in the cap. I am also aware that container tops, such as salt shakers, have been provided with spouts which are separately formed and pin-pivoted to the cover to close a pouring opening, and which may be moved to pouring position. All of these prior devices are either 10 too costly, or are mechanically imperfect.

It is an important object of this invention to provide a spout-forming element which is an integral part of the material of the cap, and which is of the same thickness as that material, and which has side-forming elements which cooperate with a portion of the body of the cap to secure the spout in operative position for pouring.

Features of the invention include all the details of construction, along with the broader ideas 25 of means inherent in the disclosure.

Objects, features and advantages of the invention will be set forth in the description of the drawing forming a part of this application, and in said drawing

30 Figure 1 is an outer face view of a milk bottle cap embodying the principles of this invention;

Figure 2 is an inner face view;

Figure 3 is a face or outside view with the spout operatively positioned for pouring; and

35 Figure 4 is a diametric section on line 4—4 of Figure 3.

It will be noted that in the drawing, the material of the cap has been shown as laminated. However, this has only been done to show the 40 line of cleavage between portions of the paper material, resultant naturally from its method of manufacture. Of course, no limitation is intended by this statement, because in some instances the cap may be formed by pasting two 45 elements together. Quite frequently, milk bottle caps or other receptacle covers are made of two pieces of material pasted together.

For convenience of description only, a two-ply construction is numerically referred to. Numerals 1 and 2 respectively indicate first and second, or inner and outer plies of the cap material. To form the larger portion of the spout, the front lamination is cut as at 3, 4, 5, 6 to form 50 a somewhat tri-angular tab 8 which is connected to the lamination 1, only on line 9, which line

may indicate scoring as by pressing. This cutting provides a recess 10, shown in Figure 3.

The inner lamination 2 is cut out as at 13, 14, 15 to form substantially a horseshoe-shaped pouring opening, of less area than the tab 8, and to also provide a tab 16 of corresponding area. The tab 16 is bendable along a cut, made at 17, which cut does not extend entirely through the lamination 2. Bending is thus facilitated. The tab 16 is cut as at 19 to facilitate bending and the tab 8 is also cut partly through as at 20, along the same line as the cuts 19 of the part 17. This slitting provides, in the case of the element 8, portions 21 which are bendable toward one another, and in case of the tab 16 provides portions 15 22 which move with the portions 21. A spout is thus provided having the same thickness as the body of the cover or cap.

The inner edges 25 of portions 21 lie within the depression 10, as best shown in Figure 4, and the outer corners 26 engage against the sides of the depression 10 as stops to prevent outward movement and to secure the side-forming elements of the spout, as well as the spout itself, in operative position. The opening formed by 25 the cuts 13, 14 and 15 functions as a pouring opening, which (see Figure 1) is normally closed by the spout-forming element 21, when this element is in recess 10.

When the rear edge of the elements 21 are 30 engaging the bottom of the recess 10, the spout is held substantially at the angle shown in Figure 4, and the resiliency of the material tends to force the elements 21 outwardly in the direction of the arrows, see Figure 3, against the sides 35 of the recess 10. In practice, this force is considerable inasmuch as the elements 21 and 22 are bent upwardly against the resilient action of the material, and after being brought to the position of Figure 4 and released they exert an outward 40 pressure, and thus a kind of frictional lock is obtained.

It will be noted that the thickness of the spout portion is the same thickness as the body portion of the cap, and this spout is substantially composed of two non-coplanar parts of unequal area. Both parts have, in addition, portions which are bendable against the resiliency of the material, to form the sides of the spout, and the cap has the recess 10 resultant from operations by which 50 one of the parts is formed. One of the parts is conditioned for bending by cutting, and this cutting provides a pouring opening which is of less area than the area of the other spout-forming portion. The portion which is cut out to form 55

the opening normally closes this opening when the other portion is in the recess.

Referring to Figure 1: The spout-forming element also acts as a tab by which the cap can be removed from the bottle, and in order to facilitate pulling out and gripping, its top is cut away as at 27. In some instances, this cut-away portion is dispensed with, however, and an extra tab 30 is formed on the spout-forming tab 8. For this purpose, the tab 8 is cut through as at 31 to intersect the scoring cuts 20-20, to give the somewhat circular tab 30 which is integral with the material along bend line 31. A reenforcing wire staple 33 is arranged at the bend line, as shown. The tab 16 forms a backing for the recess 35, formed by cutting to provide the pull-tab 30. The tab 8 is also cut as at 36 to provide for the introduction of the finger nail beneath the flap 30 to move it to a position where it can be grasped by the thumb and forefinger. It will be understood, of course, that the tab 30 may be dispensed with, in which case the apical portion of the spout-forming element will be cut as at 27. In case the tab 30 is used, this cut 27 will not be made and the cut 36 will be made instead. The use of the pull tab 30 is advisable so that the fingers do not touch the end of the spout, which is more sanitary.

Separate features of the invention include: 30 the use of a swingable spout-forming portion having portions which are bendable and the provision of means on the cap with which these bendable portions are engageable to secure the spout in operative position; the integral relation 35 of the swingable spout-forming portion to the cap; the reenforced two-ply spout-forming portion; the formation from resilient material with the arrangement such that the side-forming portions, by their resiliency, act to secure the spout 40 in operative position; the use of the sides of a recess as stops with which the side-forming portions are engageable; the use of two superposed movable integral spout-forming portions; the use of two-ply paper with one of the plies cut to 45 provide an integral portion which normally lies in the depression formed by cutting and which closes and seals an opening in the other ply; and generally all details of construction shown, or disclosed.

50 There is no intention to be entirely limited to exact structure, because a single new feature herein, is the integral spout-forming portion in which the sides of the spout cooperate with the body portion of the cap to secure the spout in 55 operative position.

Again it is to be noted that the invention includes the use of paper material, such as cardboard, which has at least one natural line of cleavage, as distinguished from material which 60 is composed of two laminations glued together. The various cuttings are made from opposite sides and are a few thousandths of an inch deeper than half the thickness of the material. By these cuts, the line of cleavage is determined. 65 It is believed this is a new departure in the manufacture of caps, and, of course, particularly as applied to formation of an integral spout having a thickness equal to that of the cap or cover material.

70 It will be noted that the creases or scoring represented by the lines 19 of Figure 2, and the knife-cuts represented by the numerals 20 of Figure 1 are substantially parallel, but are not in exact opposition to one another at opposite 75 sides of the cap, but the lines 19 are about one

thirty-second of an inch each closer to the center line than the lines 20, to insure correct bending. This is a feature.

The hair-cut represented by the line 17 is about .005 of an inch deep and is substantially in opposition to the score line 9, see Figure 1, and both lines are spaced inwardly from the base cuts 3-4, or toward the center of the cover. Therefore, the edges 25-25 are caused to tightly engage the bottom of the notch or depression 10 to hold the spout in operative position. The manner of making the cuts and their relations are also features of the invention.

There is no intention to limit the invention to the out-springing of the sides 21 in the direction 15 of the arrow (Figure 3) as the only means for securing the spout in operative position. Since the spout is bent downwardly or outwardly along line 9 against the resiliency of the material, the tendency of the spout is to swing upwardly from 20 its position in Figure 4 and this up-springing forces edges 25 against the body of the cap and thus the spout sides are held. It is, therefore, not absolutely necessary to have a recess 10, nor to have the shoulders formed by cutting as at 25 5-6 because the rear edges 25 of the elements 21 will remain in frictional contact with the corresponding surfaces in the manner mentioned.

It is to be further noted that there is no intention to limit the invention to the location of 30 the pouring opening since this pouring opening may intersect the periphery of the cap, and, therefore, be open at one side. In this case, the cuts 5 and 6 will intersect the periphery.

It is to be further noted that the convergent 35 relation of the lines 19-19, 20-20 of the spout not only provides for convergent relation of the spout, but the more than 90 degrees angular relation of the lines 20 and 5-6 to the diameter 40 of the body (see Figure 1) results in a less than ninety degrees relation when the spout is at out-standing operative position (see Figure 4), which is of prime advantage because if this relation is not had, liquid tends to run over the sides of the spout at points 26 before the spout tip is low 45 enough for the liquid to reach the outer or narrow portion.

I claim as my invention:

1. A receptacle cover formed from a single sheet thickness of sheet material having a natural 50 line of cleavage, said sheet being scored from opposite sides to facilitate cleavage and define an integrally hinged flap area, a pouring opening and a recess at the outer side of the sheet of larger area than the opening, said flap area 55 being scored to define the bottom and integrally hinged side portions of a spout, with the bottom portion at the hinge line extending laterally beyond the pouring opening, and to adapt the end portions of said spout sides to abuttingly engage 60 the bottom and sides of the recess in a manner to prevent motions of the spout toward its initial closure position, and to prevent outward swing of the sides of the spout.

2. A receptacle cover comprising material having scoring on its inner and outer faces defining a pouring opening, an integral hinging line, spout and closure for the opening, and a recess at the outer side of the material, said spout and closure having at the outer side of the cover 70 scoring defining spout bottom and sides with the spout sides adapted to abuttingly engage the sides of the recess to secure the spout and its side-forming portions in operative position.

3. A receptacle cover comprising material hav- 75

ing scoring on its inner and outer faces defining a pouring opening, an integral hinging line, spout and closure for the opening, and a recess at the outer side of the material of larger area than and surrounding said pouring opening, said spout and closure having at the outer side of the cover scoring defining spout-bottom and sides, with the spout sides adapted to abuttingly engage the sides of the recess to secure the spout and its side-forming portions in operative position.

4. A receptacle cover comprising material having scoring on its inner and outer faces defining a pouring opening, an integral hinge line, spout and closure for the opening, and a recess at the outer side of the material of larger area than and surrounding said pouring opening, said spout and closure having at the outer side of the cover scoring defining spout bottom and sides with the spout sides extended laterally beyond the pouring opening, and ends of the hinge line, the inner ends of the spout sides being adapted to abuttingly engage the sides of the recess and secure the spout and its side-forming portions in operative position.

5. A closure cap comprising material having scoring on its inner side defining a pouring opening and a portion of a spout having integral hinging connection with the material, and having scoring on its outer side defining a recess which surrounds the opening and defines another part of said spout, including foldable spout sides, the inner ends of each side being adapted after side-folding to abuttingly engage the bottom and a side wall of the recess to secure the spout and sides in operative position.

6. A closure cap composed of two ply material, scoring through one ply defining an integral flap and a pouring opening, and scoring through the other ply defining a recess and another integral flap both larger than the first mentioned flap and which normally lies in the recess to close the opening, said flaps being opposed to one another and being bendable to together form a spout, and both flaps having scoring which defines sides for the spout, the ends of the sides being adapted to engage the sides of the recess to secure the same in spout-forming position.

7. A bottle cap composed of two ply material, scoring on the outer side of one ply defining an integral flap and a pouring opening, and scoring on the outer side of the other ply defining a recess and another integral flap, both larger than the first mentioned flap and which normally lies in the recess to close the opening, said flaps being opposed to one another and being bendable to together form a spout, and both flaps having scoring which defines sides for the spout, the ends of the sides being adapted to engage the sides of the recess to secure the same in spout-forming position, the outer side of the second mentioned flap being scored to define a hinged tab for pulling the tabs to spout-forming position.

8. An article of manufacture composed of sheet material providing a single recess only in one face and a pouring opening within the confines of the recess, a hinged spout having hinged spout-side-forming portions, the spout as a whole adapted to enter the recess and having a bottom which enters and closes the opening, said spout being adapted to be held in pouring position by abutting engagement of the inner ends of said spout-side-forming portions with the bottom of the recess and by abutting engagement of the

side-forming portions with the sides of said recess.

9. A receptacle cover composed of suitable sheet material scored and cut inwardly from the inner face to define and provide a pouring opening and the bottom and part of the sides of a hinged pouring spout, which spout normally fits within and sealingly closes said opening, said cover being cut inwardly from outer face to define and provide the remainder of said spout sides and to define a recess for said remainder of said sides within which they normally sealingly lie and fit, which recess extends outwardly from and in part surrounds said opening, the innermost portions of said sides being adapted after the spout is swung to pouring position to abut the outlying portion of the bottom of said recess and engage the sides of said recess to hold the spout and sides in pouring position.

10. A receptacle cover composed of suitable sheet material scored and cut inwardly from the inner face to a depth about equal to one-half the thickness of the cover material to define and provide a pouring opening and the bottom and part of the sides of a hinged pouring spout, which spout normally fits within and sealingly closes said opening, said cover being cut inwardly from the outer face to a depth about equal to one-half of the total thickness of said cover material to define and provide the remainder of said spout sides and to define a recess for said remainder of said sides within which they normally sealingly lie and fit, which recess extends outwardly from and in part surrounds said opening, the innermost portions of said sides being adapted after the spout is swung to pouring position to abut the outlying portion of the bottom of said recess and engage the sides of said recess to hold the spout and sides in pouring position.

11. A receptacle cover composed of suitable sheet material cut inwardly from the inner face to a depth about equal to one-half the total thickness and also scored to define and provide a pouring opening and the bottom and part of integrally hinged sides of an integrally hinged pouring spout which parts normally fit and sealingly close said opening, said cover being cut inwardly from the outer face to a depth about equal to about one-half the thickness of the cover material and being also scored to define and provide the remainder of said spout sides and to define and provide a recess which extends beyond and partly surrounds said pouring opening and in which recess the remainder of said spout sides normally sealingly fit, said sides having innermost edge faces which are adapted after the spout has been swung to pouring position to abut the bottom surface of the recess at points laterally of said opening and said sides being adapted to abut the sides of said recess to be held in outwardly slanted spout-forming position against outward movement.

12. A receptacle cover composed of suitable sheet material cut inwardly from the inner face to a depth about equal to one-half the total thickness and also scored to define and provide a pouring opening and the bottom and part of integrally hinged sides of an integrally hinged pouring spout which parts normally fit and sealingly close said opening, said cover being cut inwardly from the outer face to a depth about equal to about one-half the thickness of the cover material and being also scored to define and provide the remainder of said spout sides and to define and provide a recess which extends beyond

and partly surrounds said pouring opening and in which recess the remainder of said spout sides normally sealingly fit, said sides having innermost edge faces which are adapted after the 5 spout has been swung to pouring position to abut the bottom surface of the recess at points laterally of said opening and said sides being adapted to abut the sides of said recess to be held in outwardly slanted spout-forming position against 10 outward movement, said outer surface of said material being also cut inwardly from the outer face to a depth equal to about one-half its thickness and within the confines of the area of said spout bottom-forming portion, to define and provide 15 vide an integrally hinged spout pulling flap and recess therefor, said flap normally lying in said recess and adapted to be swung outwardly therefrom.

13. An article formed from paper board having 20 scoring providing a spout and recess, which spout normally lies within the recess and between the planes of the opposite surfaces of the material in sealed relation thereto, said board and spout and recess consisting of a single piece of single 25 thickness material, which spout can be released to swing to spout-forming position thereby providing a pouring opening, and including spout side-forming portions which can be swung to spout side-forming positions and which are 30 adapted to engage the bottom and sides of the recess to hold said spout in operative position.

14. A closure comprising a one piece single thickness cleavage material having scoring defining a single hinged spout-forming flap and an 35 opening normally closed thereby and forming a recess on one face of the closure extending beyond and substantially surrounding the opening

in which said flap lies, said flap having scoring defining spout bottom and integral spout sides, said spout sides being adapted for engagement with the side walls and the bottom of the recess at a point laterally of the opening to hold them 5 and the spout in outstanding operative position.

15. A receptacle closure comprising cleavage material having scoring on its outer side defining a spout-forming portion having a spout bottom having a hinge line at its base juncture 10 with said closure, said bottom having hinged spout sides with the innermost edges of which adjacent said bottom extending laterally of a line parallel to said hinge line.

16. A receptacle closure comprising cleavage 15 material having scoring on its outer side defining a spout-forming portion having a spout bottom having a hinge line at its base juncture with said closure, said bottom having hinged spout sides which extend across a line coinciding with said 20 hinge line with the innermost edges of said sides lying substantially parallel to said hinge line.

17. A receptacle cover formed of a sheet of cleavage material having scoring extending inwardly from its outer face to the plane of cleavage and defining a trough forming portion capable of being split from the cover, and having additional scoring extending from its inner face to said plane of cleavage and defining a pouring opening which the said trough forming portion 25 normally covers, said trough forming portion including a spout bottom integrally hinged to said cover and scoring defining integrally hinged trough sides, the end edges of the trough sides adjacent the hinge of the spout bottom extending 30 laterally from the spout bottom.
